(57) **CLAIM**

The ornamental design for a mixing bottle, substantially as shown and described.

DESCRIPTION

FIG. 1 is a perspective view of a mixing bottle; FIG. 2 is a front view of the mixing bottle of FIG. 1; FIG. 3 is a back view of the mixing bottle of FIG. 1; FIG. 4 is a right side view of the mixing bottle of FIG. 1; FIG. 5 is a left side view of the mixing bottle of FIG. 1; FIG. 6 is a top view of the mixing bottle of FIG. 1; and FIG. 7 is a bottom view of the mixing bottle of FIG. 1. FIG. 8 is a perspective view of a mixing bottle; FIG. 9 is a front view of the mixing bottle of FIG. 8; FIG. 10 is a back view of the mixing bottle of FIG. 8; FIG. 11 is a right side view of the mixing bottle of FIG. 8; FIG. 12 is a left side view of the mixing bottle of FIG. 8; FIG. 13 is a top view of the mixing bottle of FIG. 8; and FIG. 14 is a bottom view of the mixing bottle of FIG. 8. FIG. 15 is a perspective view of a mixing bottle; FIG. 16 is a front view of the mixing bottle of FIG. 15; FIG. 17 is a back view of the mixing bottle of FIG. 15; FIG. 18 is a right side view of the mixing bottle of FIG. 15; FIG. 19 is a left side view of the mixing bottle of FIG. 15; FIG. 20 is a top view of the mixing bottle of FIG. 15; and FIG. 21 is a bottom view of the mixing bottle of FIG. 15.

(Continued)

FIG. 22 is a perspective view of a mixing bottle; FIG. 23 is a front view of the mixing bottle of FIG. 22; FIG. 24 is a back view of the mixing bottle of FIG. 22; FIG. 25 is a right side view of the mixing bottle of FIG. 22; FIG. 26 is a left side view of the mixing bottle of FIG. 22; FIG. 27 is a top view of the mixing bottle of FIG. 22; and FIG. 28 is a bottom view of the mixing bottle of FIG. 22. FIG. 29 is a perspective view of a mixing bottle; FIG. 30 is a front view of the mixing bottle of FIG. 29; FIG. 31 is a back view of the mixing bottle of FIG. 29; FIG. 32 is a right side view of the mixing bottle of FIG. 29; FIG. 33 is a left side view of the mixing bottle of FIG. 29; FIG. 34 is a top view of the mixing bottle of FIG. 29; and FIG. 35 is a bottom view of the mixing bottle of FIG. 29. FIG. 36 is a perspective view of a mixing bottle; FIG. 37 is a front view of the mixing bottle of FIG. 36; FIG. 38 is a back view of the mixing bottle of FIG. 36; FIG. 39 is a right side view of the mixing bottle of FIG. 36; FIG. 40 is a left side view of the mixing bottle of FIG. 36; FIG. 41 is a top view of the mixing bottle of FIG. 36; and, FIG. 42 is a bottom view of the mixing bottle of FIG. 36. The broken lines which define the bounds of the claimed design form no part thereof.
